UNITED STATES PATENT OFFICE

REGINALD A. FESSENDEN, OF WASHINGTON, DISTRICT OF COLUMBIA, ASSIGNEE, BY
MESNE ASSIGNMENTS, TO SAMUEL M. KINTNER, OF PITTSBURGH, PENNSYLVANIA,
AND HALSEY M. BARRETT, OF BLOOMFIELD, NEW JERSEY, RECEIVERS.

METHOD OF SIGNALING.

1,050,728.

Specification of Letters Patent. Patented Jan. 14, 1913.

Original application filed July 27, 1905, Serial No. 271,539. Divided and this application filed August 21, 1905. Serial No. 275,165.

To all whom it may concern:

Be it known that I, REGINALD A. FESSENDEN, a citizen of the United States, and resident of Washington, District of Columbia, have invented a certain new and useful Method of Signaling, of which the following is a specification.

The invention described herein relates to certain methods of signaling generally, but 10 more particularly to signaling by electromagnetic waves.

The primary object of my invention is to eliminate interference and increase the intensity of signals, by operating the indicator at the receiving station by the conjoint energy of the received electric impulses, and certain coöperating currents produced locally at the receiving station. This application furthermore contemplates 15 the production of signals by means of harmonic beats produced between the currents of the received electric pulses and the locally produced cooperating electric pulses, the indicator being moved by the energy 20 of the combined currents and therefore being under control, as to the frequency of motion, by the receiving operator.

The invention is hereinafter more fully described and claimed.

In the accompanying drawings, forming 30 a part of this specification, Figure 1 is a diagrammatic view illustrating a sending station; Fig. 2 illustrates a preferred manner of driving and controlling a high frequency generator. Fig. 3 is a diagrammatic view of a combined sending and receiving station; Fig. 4 is a view similar to Fig. 3, illustrating modifications, and Fig. 40 illustrates my improvements applied to line wires.

A great source of trouble in telegraphing is the liability of signals being interfered with by disturbances either atmospheric or those radiating from a station or stations other than that from which it is desired to receive signals. These and other difficulties are overcome by the methods described herein, great sensitiveness is obtained, and a number of messages, signals or indications can be sent and received at the same time, and further, these results can be obtained without making use of resonance,

although resonance effects may be used if desired and are preferably used for some purposes.

In the practice of my invention, I prefer to use for sending a means for producing continuous radiation, which may be for example the high frequency generator having the characteristics described in Patent No. 55 706,737 or the means described in Patent No. 706,742. It is also preferred to use low voltage, as by the use of comparatively low voltage, which is especially adapted for use with this improvement, and a practically continuous emission of waves, except as effected by the signal producing means (as the key) the effects of sunlight are largely overcome, interference with neighboring stations is reduced and received signals are selected more sharply. It is also preferred to employ an aerial having a large capacity as described in U. S. Reissue Patents 12,168; 12,169; and horizontally arranged as in U. S. Patents 706,738; 706,739 60 and 753,864. 70

For receiving it is preferred to employ an aerial similar to that used for sending, though a different one may be used. The aerial or collector may have more inductance and less capacity relatively to the sending conductor. A circuit through which the received oscillations will flow may be arranged in operative relation to the receiving antennae. A frequency determining 80 element controlling a locally produced field adapted to produce an interaction with the electrostatic or electromagnetic field produced by received oscillations, is used at the receiving station. 85

As a frequency controlling device, it is preferred to use a high frequency alternator, or any other suitable device for producing unintermittent oscillations, as for example, a device operating by direct current with or without discharge gap, as described in Letters Patent No. 706,742, or a selector device as described in U. S. Patent 793,652, where a high frequency alternator is used, in which latter case the field is 95 placed near the axis of rotation to avoid centrifugal effects, it may be driven by a steam or gas turbine, or by an electric motor 100 supplied from storage batteries 52 and

the frequency is preferably maintained constant to about one-tenth (1/10) of one per cent. (1%), by attaching a Weston tachometer 54 to the shaft of the motor and placing an adjustable contact on the indicating pointer of the tachometer, so that when the speed rises or falls, a suitable mechanism such as rheostat 53 will change the resistance in the field or armature of the motor, 5 and thereby restore the speed to its proper value, as shown in Fig. 2. Other means of regulation may be used, but that described is preferred, as the adjustable contact of the Weston tachometer is capable of being 10 adjusted to any desired point, and, when so adjusted, the speed is automatically maintained constant at that value.

In order to determine whether or not the frequency has the proper value irrespective 20 of mechanical means, a local independent resonant circuit (comprising a condenser, preferably a compressed air condenser, and in inductance and a sending or receiving device) may be kept on the station for the 25 purpose of forming a standard of frequency.

While a variety of forms of receiving devices may be employed, the construction shown in Fig. 3 is convenient and desirable. 30 This form consists of a light coil of wire, 8, attached to a telephone diaphragm, 9, and a second coil, 10, arranged in operative relation to the coil 8, which is arranged in operative relation to the receiving antennae. 35 Impulses generated and determined by the frequency determining element, for example, the current from the high frequency dynamo, 5, or a transformer 11, connected therewith, flow through the coil, 10. In 40 the circuit of the coil 10, an inductance 12, and a capacity 13, both preferably variable, may be placed, and the phase of the current from the dynamo may be made to have any desired value.

45 In Fig. 1 is shown a form of sending apparatus consisting of an antenna, 1, having a horizontal portion, 2, an inductance 3, and a capacity, 4, (both preferably adjustable) for tuning purposes where this is desired. 50 A high frequency alternator, 5, is operatively connected to the antenna 1, preferably through the transformer, 16. A key 7, or other suitable means, is employed for regulating or controlling the emissions of 55 radiations from the antenna either by direct make or break as shown or by changing the intensity or frequency of the emitted radiation. The method of using the key to effect a change in the character or amount of 60 the radiation while keeping the load on the generator constant, shown in Fig. 3 by the contact 36, capacity 48, and inductive resistance 37 is preferred. On the receipt of oscillations, current will flow through the 65 coil 8, and the oscillating field so produced

will interact with the field produced by the coil 10. If the field from the coil 10, which is continuously active, is of a frequency exactly the same as of the field from coil 8, produced by the received oscillations, no indication, or only a weak one, may be produced, as the phase of the current may not be suitable, the force exerted during one part of the cycle being counterbalanced by force in the opposite direction during the other part of the cycle, as is well known. It is preferred, therefore, to have the frequency of the dynamo producing a field from coil 10, different from the frequency of the received oscillations, and this difference may 70 amount preferably to about one-fifth (1/5) of one per cent. (1%), though a larger or a smaller difference may be used. If the frequency of the transmitted waves be 100,000 per second, and the frequency of the alternator 8, be one-fifth (1/5) of one per cent. (1%) different from this; *i. e.* 100,200 beats 75 will be produced, which will cause the telephone diaphragm to vibrate and emit a musical note. If the frequency difference be too 80 great, either beats will not be produced at all, or their pitch will be too high to be audible; while if the frequency difference be too small, the pitch of the beats will be too 85 low to produce a musical note or even to 90 produce an audible indication. The pitch 95 of the note may be altered at will so as to produce mechanical resonance with the telephone diaphragm, or with a resonator of 100 any desired type, by changing the speed of the alternator 5. When in calling up the 105 station beat tuning is used as it may be though it is not preferred, then after the 110 station is called up the desired beat frequency can be obtained by adjusting the position of the fixed contact or the Weston 115 tachometer relay or other speed regulating 120 or frequency determining device.

If it is desired to send while receiving, the 115 key 7 is depressed so as to make a signal, 11 and the alternator 5 generates electromagnetic waves in the antenna by means of the 120 transformer 16, whose secondary is operatively connected to the aerial 1. In this 125 case the transmitted oscillations will produce no indication on the telephone diaphragm 9, because the frequency of the sending 130 oscillations which oscillate in the antenna 1, and coil 8, will be the same as those in the coil 10, and hence no beats will be produced. The interaction between the coils 8 and 10, due to the sending, can be made 135 smaller by changing the phase in the coil 10, by means of the adjustable inductance 12, or adjustable capacity 13, so as to make the 140 phase of the currents in coil 10 and 8 different by 90°.

Another form of receiver is shown in Fig. 4, consisting of a ring, 14, preferably oval or 145 oblong, movably suspended or supported in 150

such relation to the coils 8 and 10, as to be within the influence of the fields produced by said coils. The ring or circuit 14, is adjusted to such an angle that the current produced by received oscillations in coil 8, will generate currents in the ring. The coil 10 which, as stated, is connected to the alternator through the variable inductance 12 and variable condenser 13, produces a magnetic field, which interacting on the currents in the ring 14, causes the latter to move. The motion of the ring can be utilized to produce an indication in any of the many ways known in the art. The electrical constants of the ring, e. g. its resistance or self-inductance, may be empirically arranged so as to produce a maximum effect; and with a similar end in view, the phases of the current in the coil 10 may be altered so as to give a maximum effect in the ring by means of the capacity 13, or the inductance 12.

It will be understood that, although it is preferred to use the same generator for producing a field by the coil 10, and also for sending, independent generators may be used for these purposes, as shown in Fig. 4. As shown in Fig. 3 two or more signals, indications or messages may be sent at the same time by the employment of two or more dynamos, as 5 and 15, the alternator 15 having a frequency different from that of the alternator 5, and being operatively connected to the antenna 1, preferably through a transformer 16. A key 17, or other suitable means, is employed for controlling the emissions produced by the alternator 15.

In Fig. 4, two or more signals, indications or messages may be received simultaneously, in which case a second receiver, consisting of a coil, 18, secured to a diaphragm 19, is operatively connected to the aerial, and a fixed coil, 20, is in circuit with an alternator, 21, a variable inductance and a variable capacity being also preferably included in the circuit. The frequency of the alternator 21, should preferably be different from that of the alternator 5.

Where it is desired to send two or more messages, or receive two or more messages simultaneously, it is preferable to have the alternators of such periodicities that no beats or inaudible beats, will be produced between the alternators used at the same station. Where desired, all or any of the circuits may be electrically tuned in accordance with methods well known in the art, the advantages and effects of such tuning being well known.

Instead of using the arrangement of Fig. 3 for maintaining the load on the generator constant, in which the contact 36, condenser 48 and inductive resistance 37 are used, as previously described, I may accomplish the

same purpose by opening the switch 40 above the coil 37, in which case the fixed contact of the key 7 is attached to a spring 33 fixed on the support 34 and carrying the insulating rod 28. It has a contact 29. In normal position of the key the contacts 29 and 30 are connected, completing the circuit which contains inductance 32 and condenser 31, the resistance 35 and the generator 5. On depressing the key 7 the circuit including the fixed contact on spring 33, the primary 6 of the transformer, and the generator 5, is closed and waves are sent out, and the contacts 29, 30 are separated by the downward movement of the rod 28, thereby opening the circuit 32, 31, 35, 5, 29. The release of the key 7 again opens the circuit 33, 6, 5, 7, and closes the circuit last above described. In this way the electrical constants of the generator circuit are maintained the same whether the key is depressed or not.

The ring 14, may be used to close and open a circuit, and thereby operate a bell or other indicating instrument of a relay, as shown in Fig. 4, the ring being suspended by a fine phosphor bronze wire, 22, and provided with a contact point 23, adapted to be moved into contact with a point, 24, by the movement of the ring, and so close a circuit containing a battery 25, and bell or other indicating instrument, 26. A relay 27, may be included in this circuit and employed to operate any desired mechanism for sending out the received signal from the same or a different antenna for the purpose of relaying the signal or message. In the arrangement shown in Fig. 4, the relay operates a key 38, to cause the high frequency generator, 39, to send out signals from the antenna, 1. The generator 39, may be connected to an independent antenna if preferred. The sending key, or other signal controlling mechanism, whether operated by hand, by a relay, or otherwise, in lieu of making and breaking a circuit, may be used to alter the intensity or change the frequency.

The advantages of this system are numerous, as it is applicable not only to signaling by electromagnetic waves, but also to the transmission of signals by induction by line wires and by other means. Its advantages in regard to all these methods are very great, and it is especially valuable for transmitting by electromagnetic waves. This method is practically independent of resonance (though resonance circuits may be used if desired) and hence the selectively can be, and is necessarily very sharp, being independent of resonance. A station less than one hundred feet away cannot interfere with the receipt of signals, or even weaken them if its frequency differs more than a fraction of one per cent. (1%) from that of the impulses, which it is desired to receive. The ability to send and receive at

the same time and to work multiplex is also a great value; as is also the case of operation in sending and receiving simultaneously by this method, as the sending does not interfere at all with the receipt of messages. Another advantage of using the beats method, instead of having the frequency at the receiving end the same as that of the sending end, is that if the frequency at the receiving end were the same as that at the sending end, which, however, is commercially impracticable, the fixed coil would generate by induction currents in the movable coil, many thousand times greater than the currents which it is desired to receive, and hence the effect of the impulses which it is desired to receive would be swamped by the currents generated by the local fixed coil.

20 The use of a constantly active frequency determining element is very important, as it enables the locally generated impulses to be maintained at a constant intensity, and not to die off as trains of waves do. Where 25 the intensity dies off, the effects produced would vary greatly, and to such an extent that it would not be possible to operate practically and commercially. In the method described herein a greatly intensified effect is obtained and also great certainty 30 of operation by maintaining the frequency determining element at the receiving station in a constantly active condition, and also by using at the sending station apparatus 35 producing a practically continuous emission of radiation of a frequency slightly different from that of the frequency determining element at the receiving station.

40 As by the invention described herein signals may be simultaneously sent and received with absolutely no mutual disturbance, the invention is especially adapted for relaying. In connection with line wires and 45 in the arrangement of Fig. 5 the frequency of the oscillation is made considerably lower and signals may be produced by shifting the phase of the transmitted impulses by shunting an inductance or capacity across 50 the key, so that when the key is closed, the inductance or capacity of the whole circuit is altered. The sending or receiving aerials or both may be dead beat or non-resonant to any particular periodicity. Two or more 55 aerials may be used at the station, one for sending, one for receiving, and one for relaying, but aerials are not necessary, as the magnetic component methods described in Patent No. 1,020,032 granted March 12, 60 1912, may be used. Where desirable the aerials may be tuned to a given frequency and where two or more antennæ are used they may have a common portion and the different sending or receiving devices may 65 be placed in the branches as is well known

in the art. This may also be done in the case where the sending or receiving conductors are not resonant but are practically dead beat.

The apparatus herein described, is 70 claimed in my application No. 271,539, of which application this is a division, and so is not claimed here, but

What I do claim as my invention and desire to secure by Letters Patent, is, 75

1. In the art of electric signaling, the method which consists in moving an indicator at the receiving station by the interaction of the received impulses forming the signal, and a series of sustained electric impulses locally produced at the receiving station and maintained with a frequency near to but not the same as the frequency of the received impulses. 80

2. In the art of signaling, the method 85 which consists in making an indication by the interaction of received impulses of sustained frequency and amplitude with impulses of neighboring frequency generated by a constantly acting local source of energy 90 at the receiving station.

3. In the art of signaling, the method which consists in sending sustained oscillations and producing a signal at the receiving station by interaction of a field of force produced thereby, with a field of force produced by impulses continuously generated by a local source at the receiving station, having a frequency so differing from that of the received impulses as to produce beats. 95

4. In the art of signaling with high frequency currents, the method which consists in sending sustained oscillations, maintaining at the receiving station a constantly acting field of force, producing a coöperating 105 field of force by the received impulses interacting with the locally produced field, and controlling such interaction by a constantly operating frequency determining element. 100

5. In the art of signaling with high frequency currents, the method which consists in producing at the receiving station a constantly active field of force excited by received oscillations, and a constantly active field of force excited by locally produced 110 oscillations, causing the said two fields to interact and controlling such interaction to produce signals, by a constantly operating frequency determining element. 115

6. The method of signaling which consists 120 in sending sustained oscillations, and producing by them at the receiving station a field of force, maintaining a second field of force by sustained oscillations locally produced, causing the two fields of force to interact, and controlling such interaction by a frequency determining element so as to form beats by the interaction. 125

7. The method of signaling which consists 130 in sending sustained oscillations of one fre-

quency and producing at the receiving station a coacting field of force excited thereby, and maintaining a second field of force excited by locally produced constantly sustained oscillations of neighboring frequency to those received, whereby beats are produced, substantially as described.

8. The method of signaling which consists in receiving constantly sustained oscillations and producing a field thereby, causing interaction of said field with a field excited by locally produced constantly sustained oscillations, and causing beats only when the locally produced oscillations slightly differ in frequency from those received.

9. In the art of signaling, the method which comprises maintaining continuous high frequency oscillations for absorption by a receiving antenna, providing a local circuit to absorb energy at the same rate, and supplying energy locally, and connecting said local source alternately to the local absorption circuit and to the antenna in working the operating key, whereby to maintain 25 the load on the source constant irrespective of the position of the key.

10. The method of transmitting and receiving sustained alternating signal impulses, which consists in transmitting a continuous wave train of sustained oscillations, producing signals by changes in the frequency of such wave train too small to be effectively observed by electrical resonance, and observing the minute variations in frequency of such transmitted wave train.

11. The method of transmitting and receiving sustained alternating signal impulses, which consists in transmitting a continuous wave train of sustained oscillations, changing the frequency of such continuous wave train to produce signals, combining with such transmitted wave train at the receiver locally generated sustained oscilla-

tions and observing the combined effects of such oscillations.

12. The method of transmitting and receiving sustained alternating signal impulses, which consists in transmitting a continuous wave train of sustained oscillations, changing the frequency of such continuous wave train to produce signals, combining with such transmitted wave train at the receiver locally generated sustained oscillations of a different frequency and observing the beats produced by the combination of the effects of such oscillations.

13. The method of transmitting and receiving sustained alternating signal impulses, which consists in transmitting a continuous wave train of sustained oscillations, combining with such transmitted wave train at the receiver locally generated sustained oscillations of different frequency producing by combination with the transmitted wave train a definite beat rate, changing the frequency of the transmitted wave train to transmit signals producing at the receiver a different beat rate, and observing either or both beat rates.

14. The method of transmitting and receiving sustained alternating signal impulses, which consists in transmitting a continuous wave train of sustained oscillations, changing the frequency of said wave train to produce signals, combining with such transmitted wave train at the receiver locally generated sustained oscillations and observing such combined oscillations by a receiver adapted to discriminate between the beat rates resulting from the different frequencies.

Signed at Brant Rock, Plymouth county, Mass., this 19th day of August, A. D. 1905.
